J. M. CESA

AIR HEATING ATTACHMENT FOR FIREPLACES

Filed Feb. 11, 1926

BY George J. Weller
ATTORNEY

UNITED STATES PATENT OFFICE.

JOSEPH M. CESA, OF ANTIOCH, CALIFORNIA.

AIR-HEATING ATTACHMENT FOR FIREPLACES.

Application filed February 11, 1926. Serial No. 87,516.

This invention relates to improvements in devices for heating a body of enclosed air to be used in heating different rooms by means of a fire built in an ordinary open fireplace.

The present invention particularly represents an improvement over the structure shown in my application for patent filed March 9th, 1925, Serial No. 14,116, my principal object now being to provide an apparatus for the purpose of a simpler nature and so constructed that a greater body of air is exposed simultaneously to the action of the fire and for a longer time, over what was possible with the previous device and without increasing the size of the air container.

As a result I have found from actual experience that I am able to heat an entire house having a considerable number of rooms by means of a fire of ordinary size in a single open fireplace.

Another object of the present invention is to arrange the apparatus in the fireplace so that gas, electric or other heat producing means may be used to heat the air instead of building a coal or wood fire.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a sectional elevation of an ordinary fireplace showing my improved air heating device installed therein.

Fig. 2 is a front view of the air drum detached.

Fig. 3 is a front view of the fireplace, with the folding doors closed.

Referring now more particularly to the characters of reference on the drawings, the fireplace A which is of standard construction comprises as usual a foundation structure 1 having an ash pit 2, which is substantially covered over at about the level of the floor 3 of the building to form the fire supporting surface of the fireplace. The fireplace has a vertical back wall 4 extending upwardly from the foundation to join

the chimney 5, and a front wall 6 projecting downwardly from the chimney a short distance so as to leave a large front opening as is customary.

My air heating attachment which is built into the fireplace during its erection, comprises a vertically disposed rectangular drum 7 which rests on the floor of the fireplace and abuts against the back wall 4, this drum extending for the full width of the fireplace. The drum extends upwardly to a point near the chimney, at which point it is formed with a horizontal and forwardly extending portion 8 which projects across the chimney. From the front end of the portion 8, which is some distance back of the front wall 6, the drum projects downwardly for a certain distance, as at 9, at a slight outward angle, the last named portion preferably tapering somewhat in thickness from the top to the bottom, and the drum terminating in a peak which extends the full width of the fireplace. This peak is a sufficient distance from the floor of the fireplace to enable a fire of reasonable dimensions being built under the drum without interfering with the draft or with the radiation of heat from the fire into the room.

The drum has a longitudinal partition 10 which extends for the full width of the drum from the bottom of the same to a point short of the peak in the portion 9. This partition therefore divides the area of the drum into two separated compartments 11 and 12, and said partition is disposed so that said compartments are of uneven size, the compartment away from the direct influence of the fire in the fireplace being the largest.

A flue 13 projects through the horizontal portion 8 of the drum to provide communication between the fire area below said drum and the chimney above the same, this flue being normally closed by a damper 13^a controlled by a pull rod 13^b.

A damper 14 of ordinary character operated from the front of the fireplace by a pull handle 15 or similar control member, is arranged to close the opening between the front wall 6 and the drum at the top thereof. By regulating the damper the size of this opening may of course be adjusted at will to suit different conditions.

An air intake pipe 16 is connected to the wide drum compartment 11 at the bottom

thereof, said pipe leading downwardly through the foundation 1 and being connected at its lower end to the discharge of a power driven blower 17 of suitable character.

- 5 An outlet pipe 18 leads downwardly from the bottom of the narrow compartment 12, in offset relation to the pipe 16, laterals 19 extending from said pipe 18 under the flooring 3 to the different rooms to be heated.
- 10 Floor or base-board registers 20 project upwardly from these laterals at desired points in said different rooms.

A rigid shutter 21 is mounted in connection with the outer face of the portion 9 of the drum for vertical sliding movement thereon, the shutter being guided in such movement by flanges 22 at the sides of the drum. The shutter is of such a height as to project to the floor while still being engaged 20 with the member 9 so as to completely shut off the fire area inwardly of said member 9 if desired. The shutter may also be raised so as to be substantially level with the bottom of the member 9 or to intermediate 25 points; being held at any desired position by a clamping screw 23 mounted on the member 9 and passing through a vertical slot 24 in the shutter.

When the shutter is down, the drum is 30 completely enclosed, and an electric heater which requires no air, may be placed in the enclosed area to heat the air passing through the drum and thus utilize the great majority of heat generated by such heater 35 for air heating purposes. If a gas burner or the like is used which requires some air, the shutter may be raised just sufficient to provide the necessary ventilation, while confining the majority of heat generated by the 40 burner. In this case the products of combustion of such burner pass up through the flue 13. If an ordinary wood or coal fire is used the shutter is raised all the way and the damper 14 is opened. In all cases, the 45 damper 13^a is independently controlled as may be necessary to take care of any gases etc. which may be present and which tend to collect at the top of the drum.

In operation with any kind of heat the air 50 is blown through the pipe 16 into the chamber 11, through which it passes for the full extent of the drum until it reaches the end of the partition wall 10 at the outer peak of the drum. The air then enters the chamber 55 12 and then passes around the same to the discharge pipe 18, being subjected during such traveling to the adjacent heated outer walls of the drum. Owing to the reduced area of the chamber 12 compared to that of the chimney 11, the air when entering the former is retarded in speed. This causes the air to be subjected to the heat for a greater length of time than would otherwise be the case.

60 The walls of the compartment 11, while

always relatively cool compared to those of the chamber 12 of course finally become heated also, so that by the time the air passes into the discharge pipe 18 said air is in a highly heated condition. Owing to the 70 peculiar shape of the drum the heat from the fire is concentrated between three angled portions thereof, providing a very high heated efficiency. The flue 13 may be used to carry off a certain amount of the gases, 75 while the majority of the products of combustion, if a wood or coal fire is used, pass to the front of the drum and up past the outside of the same through the damper controlled opening to the chimney. Both outer 80 walls of the portion 9 of the drum are therefore subjected to a continuous heat which further makes for great heating efficiency. The drum being of metal, the heated condition of the walls of said drum which face the 85 room in which the fireplace is located, aids of course in reflecting the heat from the fire into the room.

In order to close the front of the fireplace completely when desired, vertically folding 90 shutters 25, in addition to the shutter 21, may be mounted in the form of two units as shown in Fig. 3, the opposite end shutter of each unit being hinged to the adjacent 95 side of the fireplace.

From the foregoing description it will be readily seen that I have produced such a device as substantially fulfills the objects of the invention as set forth herein.

While this specification sets forth in detail 100 the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:—

1. An air heating attachment for fireplaces comprising an air drum mounted in 110 and extending across the fireplace, said drum comprising a vertical portion at the back of the fireplace, a horizontal portion projecting forwardly from the top of the vertical portion, and a third portion projecting 115 downwardly from the front of the horizontal portion and terminating short of the floor of the fireplace; a partition in the drum dividing the same into two transverse compartments, said partition being arranged to 120 provide air passage means between the two compartments adjacent the bottom of the last named drum portion, and intake and discharge pipes connected to the bottom of the first named drum portion to communicate 125 with the respective compartments.

2. An air heating attachment for fireplaces comprising an air drum mounted in 130 and extending across the fireplace, a partition dividing said drum into two transverse

compartments having communication with each other at one end; the compartment adjacent the wall of the drum nearest the back of the fireplace being wider than the other compartment, an intake pipe connected to the wider compartment at the end thereof farthest from the point of communication of the compartments with each other, and a discharge pipe connected to the corresponding end of the other compartment.

3. An air heating attachment for fireplaces comprising an air drum mounted in and extending across the fireplace, said drum comprising a vertical portion in the back of the fireplace, a horizontal portion projecting forwardly from the top of the vertical portion, and a third portion projecting downwardly from the front of the horizontal portion and terminating short of the floor of the fireplace; intake and outlet passages to and from the drum, a flue through

the horizontal portion of the drum separated from the interior of the drum, damper means in said flue, a vertically movable shutter to extend from the floor to the third drum portion, and arranged to be raised from the floor, and means for holding the shutter in any desired position. 25

4. An air heating attachment for fireplaces comprising an air drum mounted in and extending across the fireplace, said drum including a vertical portion at the back of the fireplace, a vertical partition extending longitudinally in the drum to divide the same into two compartments, the partition being arranged to provide communication between the compartments at their outer ends, and intake and discharge members connected to the two compartments respectively at the bottom thereof. 30 35 40

In testimony whereof I affix my signature.

JOSEPH M. CESA.
